UNITED STATES PATENT OFFICE.

ALBERT BACK, OF NEW YORK, N. Y.

DESIGN FOR LADIES' NECKWEAR.

SPECIFICATION forming part of Design No. 12,015, dated November 9, 1880.

Application filed August 26, 1880. Term of patent 3½ years.

To all whom it may concern:

Be it known that I, ALBERT BACK, of the city, county, and State of New York, have invented a new and Improved Design for Ladies' Neckwear, of which the following is a specification.

The object of my invention is to provide a new and original design in ladies' neckwear, of which the following is a description.

10 In the accompanying illustration specimens of my newly-designed ladies' neckwear are shown.

A series of loops, A A, of plain or fluted lace, tarlatan, or ribbon, B, are attached to a strip 15 of ruching, C, at or near one of the edges of the same. The upper ends of all the loops are to adjoin each other—that is to say, the inner edges of a ribbon or band forming one loop are in contact on the top of the loop, and the 20 outer edges are in contact with outer edges of the next loop.

The band or ribbon B may be of plain lacing,

or may have longitudinal or transverse stripes of different color, and may be plain, crimped, or fluted.

Having thus described my invention, what I claim as new, and desire to secure by Letters Patent, is—

1. The design for ladies' neckwear herein shown and described, the same consisting of a 30 row of loops of lace or ribbon attached to a strip or band of ruching, as set forth.

2. The design for ladies' neckwear herein shown and described, and consisting of a row 35 of loops of lace or ribbon attached to a strip of ruching in such a manner that the inner edges of each loop touch one another and the outer edges touch the outer edge of the next adjoining loop, as set forth.

ALBERT BACK.
